UNITED STATES PATENT OFFICE.

VICTOR von SCHLEGELL, OF NEW YORK, N. Y., ASSIGNOR TO HALE AND KILBURN COMPANY, OF PHILADELPHIA, PENNSYLVANIA, A CORPORATION OF DELAWARE.

WINDOW-FRAME.

1,249,693.

Specification of Letters Patent. Patented Dec. 11, 1917.

Continuation of application filed March 9, 1912, Serial No. 682,739. This application filed October 11, 1913.
Serial No. 794,566.

To all whom it may concern:

Be it known that I, VICTOR von SCHLEGELL, a citizen of the United States, residing in the city, county, and State of New York, have invented certain new and useful Improvements in Window-Frames, of which the following is a specification.

This invention relates to window-frames and is directed primarily to the provision of 10 a window-frame for use in a railway passenger car, especially such a car made largely or entirely of sheet-metal parts. The invention involves numerous features of novelty in the construction of a metallic 15 window-frame, the improvements relating particularly to facilitating the assemblage of the parts of a sheet-metal railway car, the securing of a window-frame in its place in a window-opening in the wall of a car, 20 the connection of the window-frame to the paneling of the wall of the car adjacent to the frame and the provision of efficient insulation against the passage of heat through the wall of the car.

25 In constructing pressed steel passenger railway cars heretofore, it has been the prevailing practice to make up the multiplicity of parts for a car wall including the numerous parts for the several window-frames 30 which are to be incorporated in the wall and after all of these parts have been properly constructed and taken to the place where the work of assemblage is performed, the wall is built up by adding the parts one after another. I have found that the work of erecting such a car is greatly facilitated and its cost materially reduced by making window-frames for railway cars in the form of complete window-units which may be shipped 35 in their complete form from a place of manufacture having special facilities for the manufacture of window-frames to a car builder, these units to be there inserted in openings in the wall of a car which wall has 40 been completed except for the insertion of the window-units. This procedure offers important advantages additional to the reduction in the cost of manufacture of the cars, particularly in that it facilitates making the window-frames so accurately that the sashes will operate therein easily and at the same time will fit so snugly as to preclude passage of air about the edges thereof to an undesirable extent. Furthermore the

manufacture and installation of complete 55 window-units of this character makes the parts of the window-frame independent of any relative movement of the parts of the wall of the car so that sagging of the parts of the wall which necessarily occurs when 60 the car is in use will not occasion distortion of the window-frame with the result that the sashes bind in the frame.

A window unit constructed in accordance with the invention comprises a sheet-metal window-sill, side-members formed of sheet-metal strips extending upwardly from the ends of this sill and one or more metallic cross-members connecting the upper ends of the side-members. Each of the side-members of the frame is made of two sheet-metal strips which are united at their adjacent edges but have insulating material inserted between those edges so that heat will not readily pass through the metal of the 70 side-members of the frame from the interior to the exterior and vice versa. One or more sashes are arranged within the frame and adapted for vertical movement in suitable guides. Above these sashes are a sheet-metal panel and a metallic curtain-box, both of which extend between the side-members of the frame and are secured thereto. These two parts, the panel and curtain-box, are secured to the inner strips of the side-members and do not contact at all with the outer strips of those members. In the manufacture of railway cars, there are always slight differences in the size and shape of the several window-openings and 80 in order that the completed car wall may have a more attractive appearance, the window-frames are so constructed as to provide for a vertical adjustment of the panel or both the panel and curtain-box upon the 85 side-members of the window-frame so that the panel may be secured in such a position that its upper edge will coat properly with the parts of the car wall immediately above the windows, such for instance, as the usual cornice running lengthwise of the car wall.

The present application is a continuation of my Patent No. 1,091,770, dated March 31, 1914, for car construction, certain features being disclosed therein, and others being improvements over the disclosure thereof.

The preferred embodiment of the invention is illustrated in the accompanying draw-

ings, in which Figure 1 is a front view of the frame, the guides for the curtain and sashes being removed, Fig. 2 is a vertical section of the unit on an enlarged scale, 5 broken away in part, Fig. 3 is a top view of the window-unit, Figs. 4, 5 and 6 are horizontal sections on lines 4—4, 5—5 and 6—6 of Fig. 2 and Fig. 7 is a sectional detail view 10 illustrating a slight modification of the construction shown in certain of the other figures.

Referring to these drawings, the window-frame is of rectangular form and consists of sheet-metal frame members secured together at their ends. The sill is shown at 15 8 and consists of a sheet-metal strip pressed into suitable form such as that illustrated in Fig. 2. The side-members of the frame are secured at their lower ends to the ends of the sill 8 20 and extend upwardly therefrom in parallel relation. Each of these side-members consists of an inner and an outer sheet-metal strip and these two strips are secured together with insulation between them preferably by having the edge of one strip overlap the edge of the other strip and the insulation between the overlapping edges. The inner strip is shown at 9, the outer at 10 and the insulation at 11. As shown in the sectional views Figs. 25 30 4, 5 and 6, the two strips 9 and 10 of a side-member have their adjacent edges overlapping and the strip of insulating material which extends the entire length of the strips 9 and 10 is located between these overlapping edges. The two strips and the insulating material are secured together in any suitable manner, as for instance, by rivets 12.

The rectangular frame is completed by 40 cross-members which connect the upper portions of the side-members. Preferably two such cross-members are employed, these being separated one from the other and one of them connecting the inner strips 9 while 45 the other connects the outer strips 10. The inner strips 9 are connected by a cross-member 13 in the form of a rail of angular cross-section. This is secured at its ends to the strips 9 in any suitable manner as by welding thereto. The outer strips 10 are connected to a cross-member 14 of channel section 50 welded at its ends to the strip 10.

The two strips of each of the side-members are provided with flanges at their non-adjacent edges. The flange 15 on each outer strip 10 is turned inwardly of the frame. These flanges 15 are provided for coaction with the exterior sheathing of the wall of the car. The window-unit constructed in accordance 55 with this invention is adapted to be inserted in a window-opening in the wall of a car by inserting the window-unit in the opening from the interior of the car. The exterior sheathing of the car is made to overlap the 60 edges of the window-opening slightly and

the window-unit is moved into the opening until the flanges 15 abut against the overlapping edges of the sheathing. The window-unit is then secured in position in the opening in any suitable manner, as for instance, by detachable bolts passing through 70 openings in the flanges 15 and openings in the coacting edges of the sheathing.

The inner edge of the inner strip 9 of each side-member of the frame is provided with 75 a flange 16 extending outwardly of the frame. This flange 16 is adapted to coact with a sheet-metal panel forming part of the car wall and extending between two adjacent window-frames. The window-frame 80 is therefore provided with attaching means for coaction with the panel. In the present instance, this attaching means is shown as a sheet-metal strip 17 secured in any suitable manner to the inner side of the flange 16 of 85 the strip 9. Its outer edge preferably extends beyond the edge of the flange 16 and is provided with a vertically disposed bead 18. When the window-unit is completed, the attaching means 17 takes the position 90 illustrated in Fig. 3. After two adjacent window-units have been installed in their openings, the edge of a sheet-metal panel is inserted between the strip 17 and the flange 16 of one window-unit and the opposite edge is then inserted under the flange of the next adjacent unit, the panel being 95 moved for this purpose in one direction and then a short distance in the other. The insertion of a panel in this manner moves each 100 of the attaching strips 17 to the relation in which they are shown in Figs. 4, 5 and 6. This form of attaching means, especially when provided with the bead 18 therein, holds the panel rigidly and prevents rattling 105 of the parts when the car is in use, the bead pressing against the panel.

A curtain-box formed of sheet-metal is shown at 19, this extending from one side-member of the frame to the other. Above 110 this curtain-box is a sheet-metal panel 20 which closes the frame above the curtain-box 19. A guide 21 is secured to each of the strips 9 of the side-members to guide the curtain in its movement and also to assist 115 in positioning the inner vertically movable sash 22. A guide 23 is secured to each strip 10 of the side-members, this guide lying between the inner and outer sashes 22 and 24. The panel 20 has the material at the lower 120 edge thereof bent toward the outer side of the window-frame as shown at 25 in Fig. 2. This lower portion of the panel is arranged to coact with the inner sash 22 so as to preclude the entrance of air into the car over 125 the upper edge of the sash 22. For this purpose, a weather strip 26 is secured to the upper portion of the sash 22 in position to coact with the lower edge of the panel 20 when the sash is in the closed position. 130

In the construction of railway cars, there is always a slight variation in the dimensions and shape of the openings for windows such that difficulty is experienced in making the several parts fit accurately. If no provision for adjustment were made, it would frequently occur that the several window-units installed in the side wall of a railway car would not coat accurately at their upper edges with the member or members immediately above the window-openings. In order to give the interior of a railway car a more attractive appearance by reason of the absence of a crack or uneven formation at the top of the window-unit, I provide for an adjustment of the vertical position of the panel upon the side-members of the window-frame. In the present instance, the panel 20 is shown as having the material at the upper edge thereof turned over and down at 27 so that this may be moved down more or less upon the vertical web of the rail 13. Near its lower edge, this panel is secured in any suitable manner to a rail 28 of angular cross-section and of such length that it extends from one side-member of the frame to the other. Below the rail 28, the material of the panel 20 is formed for coaction with brackets 29, one secured to each of the strips 9 of the side-members of the frame. These brackets 29 have vertically disposed slots in the outwardly extending webs thereof adapted to receive bolts 30 which bolts also pass through openings in the extension 25 of the panel 20. When assembling a window-unit initially, the panel 20 is mounted upon the frame with its upper extension 27 over the rail 13 and its lower extension 25 lying against the brackets 29, and the bolts 30 are inserted through the slots in the brackets 29 and the openings in the extension 25 so as to hold the panel in position. After the window-unit has been inserted in its position in the car wall, the bolts 30 are loosened and the panel 20 is then moved vertically such amount as is necessary to cause its upper edge to contact with the part of the car wall immediately above the window-unit, usually a cornice running lengthwise of the car. When the panel has been properly positioned thus, the bolts 30 are tightened up to hold the panel rigidly and additionally one or more cold rivets 31 are preferably inserted through the bracket 29 and the extension 25 of the panel to assist in securing the panel in position.

The rail 28 has supports 32 secured to and depending from its ends, these supports being provided with openings or other suitable means for receiving and sustaining the ends of a curtain roller. This roller is enclosed within the curtain box 19 which is secured in position by screws 33 engaging the rail 28 and screws 34 engaging horizontal ears formed on the plates 32. The cur-

tain-box 19 is therefore detachable to permit of inserting and removing the curtain and when in position it is mounted upon the panel 20 so that it and the panel are adjusted vertically together. The range of adjustment of these parts necessary for the purpose above mentioned is very small as it is only necessary to provide for enough adjustment to compensate for irregularities in the arrangement of the other parts of the wall. The ends of the curtain-box are closed as is indicated in Fig. 1 and extend over upon the flanges 16 of the inner strips 9 of the side-members so as to present an attractive appearance at these points.

The panel 20 preferably has its lateral edges turned inwardly as shown at 35 in Fig. 4 so that these lateral edges lie close against the inner strips 9 of the side-members of the frame. Preferably retaining strips 36 are provided for coaction with these side flanges 35 of the panel 20. These strips 36 are secured to the strips 9 and are bent intermediate their edges as shown in Fig. 4 so as to inclose the flanges 35 of the panel and hold the same rigidly in position while permitting the vertical movement of the panel necessary to properly position the panel with respect to the car wall. The strips 9 of the side-members have openings 37 (Fig. 1) in their extreme upper ends to receive bolts by which the window-unit is secured to the car wall. When these bolts are tightened up, the extreme upper edge of the panel 20 will be clamped between the rail 13 of the window-unit and the underlying part of the car wall to assist in holding the panel firmly.

Referring now to Fig. 7, a modified construction is shown whereby proper coaction of the upper edge of the window-unit with the overlying cornice is secured. The cornice is shown at 38 and its upper edge is secured to the wall structure while its lower edge is unsecured until the window-unit is tightened up in position. This cornice is formed of sheet-metal and its unsecured lower edge is capable of slight vertical movement by reason of the elasticity of the metal. In inserting the window-unit, the lower edge thereof is positioned upon the sub-sill of the car wall and then the upper portion of the unit is moved into the window-opening. As this is done, the upper edge of the panel 20 engages the portion 39 of the cornice and the latter moves upwardly sufficient to permit the edge of panel 20 to pass beyond it whereupon the cornice springs back to its original shape. When the securing means for the window-unit including the bolts 40 are tightened up, the lower edge of the cornice 38 is gripped between the upper edge of the panel 20 and the wall structure and all of the parts are held firmly.

It will be appreciated that a window-unit

constructed as herein described with the members of the frame secured rigidly to each other as by welding them together, will retain its shape so that the sashes will move 5 freely while fitting snugly therein and that when the unit is positioned with its side-members spaced from and not secured to the posts of the side wall, the sagging which takes place in the wall of the car including 10 relative movement of the posts will not cause distortion of the frame and thus bind the sashes. Furthermore, such a complete window-unit may be readily inserted in a window-opening when assembling a car wall 15 and thereafter may be readily withdrawn to permit of painting the interior surfaces of the metal parts of the window-unit and wall. Also, the construction herein described involving the provision of insulation in the 20 side-members of the frame greatly reduces the passage of heat through the window-unit from the interior to the exterior of the car and vice versa.

Having described my invention, what I 25 claim as new therein and desire to secure by Letters Patent of the United States is:

1. A window-frame comprising a metallic window-sill, two metallic side-members secured at their lower ends to the sill, and a 30 cross-member connecting the side-members near their upper ends, each of said side-members consisting of inner and outer sheet-metal strips having their adjacent edges secured together with insulating material 35 between them, the inner strip having its opposite edge flanged outwardly of the frame, and sheet-metal strips secured to the outer sides of said flanges near one edge thereof and having beads therein near the 40 opposite edges thereof, said beads being adapted to press against panels inserted between said beaded strips and said outwardly extending inner strip flanges, substantially as set forth.

45 2. A window frame comprising a sill, two metallic side members secured at their lower ends to the sill, a metallic cross-member

connecting the upper ends of the side members, a sheet-metal panel extending between the side members, and having its upper 50 edge turned to extend about the upper edge of said cross-member, in such manner as to permit some vertical movement of said panel without disengaging the upper edge of said panel from said cross-member, and 55 means for securing the panel to the side members in various adjusted positions, substantially as set forth.

3. A window-frame consisting of a sheet-metal window-sill, two metallic side-members secured at their lower ends to the sill and each consisting of inner and outer sheet-metal strips secured together with insulating material between them and extending lengthwise thereof, two separated cross- 65 members one connecting the inner and one connecting the outer strips of said side-members at the upper ends thereof, and a sheet-metal panel extending between and secured to the inner strips of said side-members, and means for securing the panel in position in various positions lengthwise thereof, the upper edge of said panel being formed to coact with the cross-member connecting said inner strips, substantially as set 70 forth.

4. A window-frame consisting of a sheet-metal window-sill, two metallic side-members secured at their lower ends to the sill, a metallic cross-member connecting the upper ends of the side-members, a sheet-metal panel extending between and secured to the side-members and having the material thereof near its lower edge bent toward the outer side of the frame, and a sash in the frame 80 adapted to coact near its upper edge with said bent lower portion of the panel, substantially as set forth.

This specification signed and witnessed this 16th day of September, 1913.

VICTOR von SCHLEGELL.
